THE NORRIS PETERS CO., PHOTO-LITHO., WASHINGTON, D. C.

UNITED STATES PATENT OFFICE.

JOHN HORTEN OGLE, OF WINDFALL, INDIANA.

FLOOD-GATE.

SPECIFICATION forming part of Letters Patent No. 697,159, dated April 8, 1902.

Application filed May 24, 1901. Serial No. 61,744. (No model.)

To all whom it may concern:

Be it known that I, JOHN HORTEN OGLE, a citizen of the United States, residing at Windfall, in the county of Tipton and State of Indiana, have invented certain new and useful Improvements in Flood-Gates; and I do hereby declare the following to be a full, clear, and exact description of the invention, such as will enable others skilled in the art to which it appertains to make and use the same.

My invention relates to what are commonly termed "flood-gates;" and it consists in certain novel features of combination and construction of parts, as will be hereinafter fully described and claimed, reference being had to the accompanying drawings, made a part of this application.

The object of my invention is to so suspend a gate or a series of gates across a stream of water that the same will prevent stock from passing from one field to another, though at the same time permit the water to flow freely in the channel of the stream.

A further object of my invention is to enable the slack or sagging condition of the cable or cables upon which the gates are suspended to be taken up and again made taut.

Other objects and advantages will be made fully apparent from the following specification, considered in connection with the accompanying drawings, in which—

Figure 1 is a perspective view of my invention complete as applied to use. Fig. 2 is a detail view showing simple means which may be employed in uniting the two coöperating cables. Fig. 3 is a perspective detail view illustrating the device employed to tighten the cables when they have become sagged or slackened by use.

The elements of my invention and their coöperating accessories will for convenience be designated by numerals, of which 1 and 2 represent the main or cable supporting posts, which are properly reinforced and sustained in place by means of the bracing-cables 3 and 4, the latter being designed to hold the strain incident to a flood in the stream.

The main cable or support 5 for the gates is properly connected in any preferred way, as by the eyebolts 6, said bolts being held in posi-

tion by being extended through a suitable aperture in the posts 1 and 2 and engaged by a nut 7 or otherwise. The main cable is reinforced and sustained by the auxiliary cable 8, also secured by means of eyebolts 9 to the posts 1 and 2, the location of the auxiliary cable being above the main cable, as clearly shown. The flood-gates proper may be made in any preferred way and of any suitable material and preferably consist of the frame-sections 10 and the intermediate sections 11, connected to the main sections in any preferred way, as by the cross-bars 12.

To the upper ends of the main sections 10 I pivotally connect the brackets or yokes 13, which are adapted to extend over the main cable 5, and thus hold the gates properly suspended, so that the lower ends thereof will extend downward in the water almost in contact with the bottom of the channel.

In Fig. 2 I have illustrated how the main and auxiliary cables may be conveniently united, preferably at their middle portions, in such a way that the auxiliary cable will brace and sustain the main cable, the connecting device comprising the tubular section 14, designed to receive a contiguous part of the main cable. The tubular section 14 is provided upon its upper side with the extension 15, provided with a suitable aperture designed to receive a contiguous part of the auxiliary cable 8. This simple means of connecting the two cables will obviate the necessity of binding the same at this point, as by extending a rope or wire around them, as is common.

The device illustrated in Fig. 2 may be modified so as to have the integral extension or handle portion 16 connected to the member 15, the said extension 16 also having the threaded terminal or stem 17, designed to fit an aperture 18, provided in the controlling-handle 19, the said handle being secured in position on said stem, as by the nut 20.

The handle 19 is so secured upon the stem 17 that it may be readily turned, so as to extend parallel with the member 14 or at right angles thereto, and when mounted in the position shown in Fig. 1 it is obvious that the handle 19 may be drawn downward, said handle being so disposed that it will readily pass

through between the middle frame-sections 10, and by said means the two cables may be tightly twisted, so as to take up or compensate for any slackening or sagging incident to the use of the gate. After the two cables have been thus twisted to the desired degree the handle 19 will be so disposed that its extreme ends will each bear against a contiguous frame-section 10, and thus prevent the handle from again moving upward and causing the cables to unwind.

I desire in this application to comprehend the use of the device illustrated in Figs. 1 and 3 or the simple device shown in Fig. 2, as I may find most expedient and desirable in practice.

If deemed desirable, auxiliary cable-supporting posts 21 for the main cable may be erected, preferably at the edge of the stream, the walls or edge of the stream being reinforced and sustained in any preferred way, as by a wooden or stone wall 22.

It is thought from the foregoing description, considered in connection with the accompanying drawings, that the construction and use of my improved flood-gate will be made fully apparent, and while I have described the preferred combination and construction of parts I desire to comprehend in this application all such substantial equivalents and substitutes

as may be considered to fall fairly within the scope of my invention.

What I claim as new, and desire to secure by Letters Patent, is—

1. The combination with cable-supporting posts, of a main cable secured thereto, an auxiliary cable connected to said supporting posts, gates having supporting means suspended on the main cable, and means for twisting together the main and auxiliary cables at their middle portions, said means connecting said cables, as set forth.

2. The combination with the cable-supporting posts, of a main cable connected at its ends to said posts, an auxiliary cable also connected to said posts, gates suspended from the main cable, a tubular section through which the main cable passes, an extension on said tubular section through which the auxiliary cable passes, and a handle portion with stem and controlling handle, said handle being adapted to be turned to twist together the cables, substantially as described.

In testimony whereof I affix my signature in presence of two witnesses.

JOHN HORTEN OGLE.
